UNITED STATES PATENT OFFICE.

CHARLES E. MCCOY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

Application filed March 19, 1921. Serial No. 453,830.

To all whom it may concern:

Be it known that I, CHARLES E. McCoy, a citizen of the United States, residing at Wilkinsburg, in the county of Allegheny and State of Pennsylvania, have invented certain new and useful Improvements in Relays, of which the following is a specification.

My invention relates to relays of the electromagnetic type, and to systems of railway signaling to which such relays are particularly well adapted.

I will describe one form of relay and one form of railway signaling system, both embodying my invention, and will then point out the novel features thereof in claims.

In the accompanying drawings, Fig. 1 is a view showing in side elevation one form of relay embodying my invention, certain parts being removed. Fig. 2 is a view similar to Fig. 1, but showing the parts which are not illustrated in Fig. 1 and omitting some of the parts which are illustrated in Fig. 1. Fig. 3 is a bottom view of the relay showing the parts which are illustrated in Fig. 2. Fig. 4 is a top view of the magnets forming part of the relay shown in the preceding views. Fig. 5 is a diagrammatic view showing one form of railway signaling system employing the relay illustrated in the preceding views.

Similar reference characters refer to similar parts in each of the several views.

Referring first to Figs. 1 to 4, the reference character A designates a plate of insulating material, such as porcelain, which serves as the support for all of the operating parts of the relay.

Mounted on the plate A is an electromagnet B which comprises, as usual, a pair of parallel cores 2 and 2^a connected at the top by a backstrap 77, each core being provided with a winding 4. Each core passes through the plate A and terminates in an enlarged pole-piece 3 or 3^a on the underside of this plate. Electromagnet B is made slow-releasing in character by suitable means, such, for example, as copper sleeves 26 surrounding the cores 2 and 2^a.

Also mounted on the plate A is a second electromagnet C which is formed in part by

portions of magnet B. One leg of magnet C comprises the two cores 2, 2^a in multiple, and the other leg is a separate core 5 the upper end of which is attached to a suitable projection or ear 77^a on the back-strap 77 and the lower end of which terminates in a pole-piece 5^a located on the under side of the plate A. The winding of magnet C, which is designated 6, is mounted on the core 5.

The relay is provided with two armatures, viz, a neutral armature 7 and a polarized armature 8. The former is shown in Fig. 1 only, and the latter in Figs. 2 and 3. 65

The neutral armature 7 is pivotally mounted in a bracket 9 attached to the pole-pieces 3 and 3^a, so that it moves towards and away from these pole-pieces in accordance with the presence and absence of current in magnet B. This armature, however, is not affected by the presence and absence of current in magnet C for the reason that it is spaced a considerable distance from pole-piece 5^a. The armature 7 carries a plurality of contact fingers 7^a, etc., which are spaced therefrom by insulating studs 10 and which co-operate in the usual manner with front contact members 11^a, etc., and with back contact members 12^a, etc., the front contacts being closed when magnet B is energized and the back contacts being closed when this magnet is deenergized. 75

The polarized armature 8 is shaped as best shown in Fig. 3; that is, it has a body portion 8^a located beneath the pole-piece 5^a, and two legs 8^b and 8^c which are disposed between the pole-pieces 3 and 3^a. This armature, then, is influenced by both magnets B and C. Armature 8 is mounted to move in two different planes. The armature itself is mounted on horizontally disposed trunnions 13, 13 which are pivoted in a T-shaped member 14, so that as far as this mounting is concerned the armature swings 95 in a vertical plane towards and away from the pole-piece 5^a. The armature is biased away from this pole-piece owing to the fact that the end 8^a is heavier than the ends 8^b, 8^c, but when magnet C is energized the end 8^a is moved upwardly to pole-piece 5^a regardless of the polarity of the current sup- 100

plied to winding 6. This response of armature 8 to the presence and absence of current in winding 6 is due to the fact that the armature bridges the gap between pole-pieces 3 and 3^a on the one hand, and pole-piece 5^a on the other. Armature 8 carries a contact finger 15 which engages with a back contact 16 or a front contact 17 according as magnet C is de-energized or energized. As will be explained hereinafter, when contact 15-17 is closed, current of fixed polarity is supplied to windings 4 of magnet B, but this current is discontinued when contact 15-17 opens.

15 The polarized armature 8 is also mounted to swing in a horizontal plane, and to accomplish this the member 14 is swivelled on two vertically disposed pivots 18 and 18^a. The upper pivot 18 is attached to member 14, from which it passes upwardly through a hole in armature 8 and is trunnioned in the pole-piece 5^a and core 5. The lower pivot 18^a is mounted in an arm 19^a which projects downwardly from a plate 19, this plate being held in position against plate A by the pole-pieces 3, 3^a and 5^a. It will be seen, then, that armature 8 can swing to one position wherein leg 8^b engages pole-piece 3, and to another position wherein leg 8^c engages pole-piece 3^a. It occupies one of these positions or the other according as current of one polarity or the other is supplied to winding 6.

Attached to the polarized armature 8 by insulating studs 20 are two contact fingers 21 and 21^a, which constitute the polarized contacts of the relay, and which co-operate with fixed contact members 22, 23, 24 and 25. These contacts are, of course, controlled by the movements of the armature in the horizontal plane, and are not affected by the vertical movement on the trunnions 13, 13^a. When the armature is in such position that the leg 8^b engages pole-piece 3, contacts 21-22 and 21^a-25 are closed, and the other two contacts are open. When the position of the armature 8 is reversed, so that leg 8^c engages with pole-piece 3^a, contacts 21-23 and 21^a-24 become closed, and the two first-mentioned contacts are opened.

The operation of the relay is as follows:

When winding 6 is de-energized, the polar armature 8 is in its released position wherein contact 15-17 is opened, so that magnet B is de-energized. It follows, of course, that the neutral armature 7 is then open, so that all of the front contacts controlled by this armature are likewise open. When current is supplied to winding 6 of magnet C, armature 18 swings upwardly around its horizontal axis, thereby closing contact 15-17, so that current is supplied to magnet B and the neutral armature 7 becomes closed. The current thus supplied to magnet B is always of the same polarity, regardless of the polar-

ity of the current in winding 6, so that as soon as magnet B becomes energized the polar armature 8 will swing around its vertical axis to one extreme position or the other depending on the polarity of the current in winding 6.

I will now assume that the polarity of the current supplied to winding 6 is suddenly reversed. This, of course, permits polarized armature 8 to swing downwardly around its horizontal axis, but this armature immediately returns to its closed position. Contact 15-17 is, therefore, open for a moment, so that magnet B is momentarily de-energized. Inasmuch as this magnet is slow-releasing, however, the neutral armature 7 remains closed during the momentary de-energization of the magnet, so that the neutral contacts of the relay are not affected by the reversal of current.

When winding 6 becomes de-energized, it, of course, releases the polar armature 8, which then swings downwardly around its horizontal axis, and the consequent opening of contact 15-17 causes magnet B to become de-energized, so that the latter magnet releases the neutral armature 7.

Referring now to Fig. 5, I have here shown a stretch of railway track L, which is divided into block sections D-E, E-F, etc., by insulated joints. As here shown, each block section is further divided by similar joints to form subsections D-G, G-E, etc. Located adjacent one end of each block section is a railway signal designated by the reference character S, with an exponent corresponding to the location, each of which signals, as here shown, is of the semaphore type, and is adapted to indicate stop, caution and proceed. In the drawings I have shown signals governing traffic in one direction only, namely, from left to right, but it is understood that in practice a corresponding set of signals would usually be provided for governing traffic in the opposite direction, which signals would be controlled by apparatus similar to that which I have shown for the control of signals S.

Each sub-section of the railway track is provided with a track circuit comprising a track battery b and a track relay designated by the reference character T with a suitable exponent.

Each signal S is controlled by a relay designated R with an exponent corresponding to the location, each of which relays is the same as that shown in Figs. 1 and 2, and explained hereinbefore.

Referring particularly to signal S^E, the caution indication circuit is from battery K^E, through wires 27, 29 and 30, contact 11^a-7^a of relay R^E, wires 31 and 32, operating mechanism of signal S^E, wire 33, contact 11^b-7^b, wires 34, 35 and 37 to battery K^E. This circuit, it will be noted, is closed

when magnet B is energized, that is, when magnet C of relay R^E is energized by current of either polarity. The proceed indication circuit for signal S^E is from battery K^E, through wires 27, 29 and 30, contact

- 11^a—7^a, wire 31, contact 21—22, wire 39, operating mechanism of signal S^E, and thence as before to battery K^E. This circuit is closed only when relay R^E is energized by current of such polarity as to close the contact 21—22, which contact is operated by polar armature 8 (see Figs. 1 and 2). Such current I will term current of normal polarity.
- 15 The magnet B of relay R^E is provided with a circuit which passes from battery K^E, through wires 27, 29, 28 and 40, contact 15—17 of polar armature 8, wire 41, windings 4 of magnet B, and wires 42, 43, 36 and 20 37 to battery K^E. It follows, therefore, that magnet B is energized by current of fixed polarity whenever magnet C is supplied with current of either polarity.

The circuit for magnet C of relay R^E passes from battery K^E, through wires 44, 45, 46 and 47, pole-changer P^E operated by signal S^E, wire 48, contact 11^c—7^c of relay R^E, wires 50 and 65, contact 51 of track relay T^t, wire 52, contact 53 of track relay T^t, wire 76, winding 6 of magnet C, wires 54 and 55, common wire O, wires 56 and 57, pole-changer P^F, and wires 58, 59, 60 and 61, to battery K^F. The polarity of the current thus supplied to magnet C is determined by the position of pole-changer P^F; the polarity is normal when signal S^F indicates proceed or caution, and reverse when the signal indicates stop.

The circuit for magnet C of relay R^F is provided with a shunt around contact 11^c—7^c, which shunt passes from wire 48, through wire 62, contact 63 of a stick relay X^F, and wire 64 to wire 65. The stick relay X^F is so controlled as to be closed when a train passes signal S^F moving toward the right, but not when a train passes along the track moving in the opposite direction. The pick-up circuit for this relay is from battery K^F, through wires 44, 45, 46, 47, 66 and 67, contact M^F operated by signal S^F, wire 68, back contact 69 of track relay T^t, wire 70, winding of relay X^F, wire 71, contact 12^d—7^d of relay R^F, and wires 72, 72^a and 61 to battery K^F. This circuit will be closed when a train passes point F, provided that at such time signal S^F indicates either proceed or caution, that is, provided contact M^F is closed. The stick or holding circuit for relay X^F is from battery K^F, through wires 44 and 73, contact 74 of relay X^F, wire 75, winding of relay X^F, wire 71, contact 12^d—7^d, and wires 72, 72^a and 61 to battery K^F. When relay X^F is once closed, it will remain closed as long as magnet B of relay R^F is de-energized, that short circuit through wires 42, 43 and 78,

is, as long as the train occupies any part of the block section through which signal S^F governs traffic.

The operation of the system shown in Fig. 5 is as follows:

Each signal normally indicates proceed, as shown in the drawing, so that magnet C of each relay R is energized by current of normal polarity. When a train moving toward the right enters sub-section D—G, the consequent opening of track relay T^t opens at contact 53 the circuit for magnet C of relay R^D, so that magnet B of this relay becomes deenergized. This opens both the caution and proceed circuits for signal S^D, so that this signal moves to the stop position. The closing of the back contact 69 of track relay T^t energizes stick relay X^D, but this has no effect on the portion of the system shown in the drawing. As the train proceeds into sub-section G—E, it de-energizes track relay T^t, so that contact 51 of this relay opens, and thereby keeps the circuit for magnet C of relay R^D open. As the train enters sub-section E—H, it opens track relay T^t, thereby de-energizing relay R^E, so that signal S^E moves to the stop position. The circuit for magnet C of relay R^D is now open at contact 11^c—7^c of relay R^E, but the branch around this contact is closed because relay X^E becomes energized due to the opening of track relay T^t. Signal S^E being in the stop position, however, current of reverse polarity is supplied to magnet C of relay R^D, so that contact 21—22 of the latter relay is opened. Magnet B of this relay is energized, however, so that the caution indication circuit for signal S^D becomes closed and this signal, therefore, moves to the caution position. As the train proceeds into sub-section H—F, track relay T^t opens and track relay T^t closes, but this has no effect on the other parts of the apparatus shown on the drawing. As the train passes point F, it opens track relay T^t, thereby placing signal S^F at stop and closing relay X^F. Current of reverse polarity is then supplied to magnet C of relay R^E, so that signal S^E returns to the caution position. In so doing, it shifts the position of pole-changer P^E, so that current of normal polarity is again supplied to magnet C of relay R^D. The reversal of the polarity of the current in this magnet winding permits contact 15—17 to open momentarily, thereby momentarily discontinuing the supply of current to magnet B of the same relay. Magnet B being slow-releasing, however, the neutral armature contacts of this relay remain closed, so that the caution indication circuit for signal S^D remains closed. The slow-releasing feature of magnet B is augmented by the fact that while back contact 15—16 of magnet C is closed, magnet B is placed on signal S^D through wires 42, 43 and 78,

contact 16—15, and wire 41. Contact 21—22 of relay R^P now closes, so that signal S^P returns to the proceed position. As the train passes out of the block section to the right of signal S^F , this signal returns to the caution position, thereby permitting signal S^E to return to the proceed position, and as the train leaves the second block in advance of point F, signal S^F also returns to the proceed position, whereupon the parts of the apparatus are restored to the conditions in which they are shown in the drawing.

When a train moving in the opposite direction, that is, towards the left, enters a sub-section to the right of point J, the opening of the track relay for such sub-section opens the circuit for magnet C of relay R^F , so that signal S^F moves to the stop position. The opening of the neutral contacts of relay R^F serves to open the circuit for magnet C of relay R^E , so that this relay also becomes de-energized and signal S^E moves to the stop position. For a similar reason, signal S^P moves to the stop position. As the train passes point F, signal S^F will return to the proceed position, and, similarly, as the train passes points E and D, signals S^E and S^P will successively return to the proceed position.

Although I have herein shown and described only one form of relay and only one form of signal system both embodying my invention, it is understood that various changes and modifications may be made therein within the scope of the appended claims without departing from the spirit and scope of my invention.

Having thus described my invention, what I claim is:

40 1. A relay comprising a slow-releasing electromagnet, a second electromagnet formed in part by the first, an armature polarized by said neutral magnet when the latter is energized and responsive in one manner to the presence and absence of current in said second magnet and in another manner to the polarity of such current, means controlled by said armature when moved in response to current in said second magnet for supplying current of fixed polarity to said first magnet, and a neutral armature responsive to the presence and absence of current in said first magnet.

55 2. A relay comprising a slow-releasing electromagnet, a second electromagnet formed in part by the first, an armature responsive in one manner to the presence and absence of current in said second magnet, means for supplying current of fixed polarity to said first magnet when said armature responds to the presence of current in the second magnet, said armature being polarized by the first magnet when energized and responsive in another manner to the polarity of the current supplied to the

second magnet, and a neutral armature responsive to the presence and absence of current in the first magnet.

3. A relay comprising a slow-releasing electromagnet, a second electromagnet, an armature responsive in one manner to the presence and absence of current in said second magnet and in another manner to the polarity of such current, means for controlling the supply of current to said first magnet by said armature, and a second armature responsive to the presence and absence of current in said first magnet.

4. A relay comprising a slow-releasing electromagnet, a second electromagnet, an armature responsive in one manner to the presence and absence of current in said second magnet and in another manner to the polarity of such current, means for supplying current of fixed polarity to said first magnet when said armature responds to the presence of current in the second magnet, and a second armature responsive to the presence and absence of current in said first magnet.

5. A relay comprising a slow-releasing electromagnet, a second electromagnet, an armature responsive to the presence and absence of current in said second magnet by movement in one path and to the polarity of the current in the second magnet by movement in another path, means for controlling the supply of current to said first magnet by said armature, and a second armature responsive to the presence and absence of current in said first magnet.

6. A relay comprising a slow-releasing electromagnet, a second electromagnet, an armature responsive to the presence and absence of current in said second magnet by movement in one path and to the polarity of the current in the second magnet by movement in another path, means for supplying current of fixed polarity to said first magnet when said armature moves in response to current in the second magnet, and a second armature responsive to the presence and absence of current in the first magnet.

7. A relay comprising a slow-releasing electromagnet, a second electromagnet, an armature pivotally mounted to swing on two axes perpendicular to each other, said armature moving about one axis in response to the presence and absence of current in said second magnet and about the other axis in response to the polarity of such current, means for controlling the supply of current to said first magnet by said armature, and a second armature responsive to the presence and absence of current in said first magnet.

8. A relay comprising a slow-releasing electromagnet having two parallel cores and a neutral winding on each core, a second electromagnet one leg of which is formed by said two cores in multiple and the other by

a third core carrying a third winding, an armature mounted to move towards and away from said third core according to the presence or absence of current in said third winding, means controlled by said armature when attracted to said third core for supplying current of fixed polarity to said neutral windings, said armature being mounted to also swing towards one or the

other of said first-mentioned cores according to the polarity of the current in said third winding, and a second armature movable towards or away from said first-mentioned cores according to the presence or absence of current in said neutral windings.

In testimony whereof I affix my signature.

CHARLES E. McCOY.
